CUTOFF CYLINDER SPRING CONSTRUCTION

Curtis S. Crafts, Oak Park, Ill., assignor to The Goss Printing Press Company, Chicago, Ill., a corporation of Illinois

Application December 13, 1947, Serial No. 791,586

1. Claim. (Cl. 164—66)

1 The present invention relates to printing presses and more particularly to an improved spring for use in a cut-off cylinder.

In conventional presses the cut-off cylinder includes a radial cutting blade which is longitudinally mounted in the cylinder and is bounded on each side by a series of blocks or cheekwoods which are biased outwardly, serving to hold the webs in place during the cutting operation. The service performed by the cut-off cylinder is extremely severe since modern presses are designed to produce up to 50,000 newspapers or more per hour, the cheekwoods being depressed each time the cut is made. When running at such high speed, particularly where a large number of webs are run together and folded prior to cut-off, it has been necessary to replace the cheekwood biasing springs which become broken, often after only a few hours of use. In an attempt to correct this difficulty, coil springs of various designs have been developed over the years which have been conservatively designed for the calculated loading and displacement. Breakage has, however, continued to be a chronic fault of a modern press and has been considered one of the penalties paid for high press output.

It is a primary object of the present invention to provide an improved spring for a cut-off cylinder which is adapted for use with cylinders of conventional design and which resists excessive strain and consequent breakage in spite of repeated and severe impact on the cheekwoods.

It is another object to provide an improved spring which is so constructed that cocking or tilting of the associated cheekwood does not cause excessive strain and which is able to withstand the loading applied thereto over a wide range of press speeds and in spite of considerable variation in the thickness of the newspaper being severed.

It is a further object to provide a spring which is particularly well adapted for individual use with a cheekwood and in which the space below the cheekwood is more efficiently used for resilient storage and partial absorption of the energy conveyed to the spring as a result of force exerted on the cheekwood. It is a related object to provide a spring inherently adapted to equalize the pressures applied to the ends of a cheekwood in spite of limited longitudinal tilting.

It is a still further object to provide an improved spring for a cut-off cylinder which not only enables a substantial reduction in spring expense but which enables the construction of the cutting assembly including the knife bar to be considerably simplified.

Other objects and advantages of the invention will be apparent from the detailed description will be apparent from the detailed description taken in connection with the accompanying drawings, in which:

5 Figure 1 is a fragmentary sectional view of the cutting cylinder showing the cutting blade, knife bar and cheekwoods in cooperative relation with the improved spring construction.

Fig. 2 is a section view taken along line 2—2 of Fig. 1.

Fig. 3 is a cross-sectional view of the leaf spring construction taken along line 3—3 of Fig. 2.

Fig. 4 is a detailed enlarged view of the improved spring construction and with the spring clamp in partial section.

While the invention is susceptible of various modifications and alternative constructions and uses, I have shown in the drawing and will herein describe in detail one embodiment of the invention. It is to be understood, however, that I do not intend to limit the invention by such disclosure, but aim to cover all modifications and alternative constructions and uses falling within the spirit and scope of the invention as expressed in the appended claims.

Referring now to Figure 1 the cut-off cylinder indicated generally at 10 has a longitudinal channel 11 machined therein in which is mounted the cutting assembly 12. Such cutting assembly includes a knife bar 14 which extends the length of the groove and which mounts a knife 15. The cutting assembly and in particular the knife bar may be rigidly fastened in the groove 11 by any desired means, for example, by means of a wedge block or gib 16 which presses against a tapered surface 18 on the knife bar. In turn, the wedge block 16 is retained in place by a series of screws 17 which are spaced at intervals

40 along the length of the bar. The knife bar is preferably formed of two opposed L-shaped sections held together by bolts 14a and defining a longitudinal channel 19 within which the knife 15 is laterally centered. Although the knife is rigidly fastened in the knife bar, it may be radially adjusted prior to being clamped in place. The knife 15 thus divides the channel 19 into two spaces or grooves 19a and 19b.

Lying within the grooves 19a, 19b are the **45** cheekwoods 20, 21. Such cheekwoods have rounded upper surfaces 20a, 21a respectively, but are otherwise generally rectangular in shape and arranged to slide loosely within the spaces provided. As shown to better advantage in Fig. 2, the cheekwoods are relatively short, conventionally about four or five inches in length and are

axially separated by a clearance of approximately $\frac{1}{8}$ inch as indicated at 24. During normal operation of the press the cheekwoods are forced radially outward, both as a result of centrifugal force and as a result of spring pressure. Outward movement is, however, limited by a plurality of cheekwood retaining pins or dowels 25 which extend across the channel 19 of the knife bar 12 and through apertures 26 in the cheekwoods. These apertures are radially elongated or slot-like so that considerable movement is permitted, the arrangement allowing one end of the cheekwood to be considerably depressed independently of the other end.

In accordance with the present invention an improved leaf spring construction is provided below each of the cheekwoods for biasing the same outwardly which is inherently adapted for the storage of a maximum amount of energy and which, at the same time, is not overstrained by serious tilting or cocking of the cheekwood. In the present instance the improved spring indicated generally at 30 includes a plurality of leaves 31, 32, 33, 34 and 35 which are graduated in size and which are prestressed so as to assume a normal bowed shape. The spring is arranged in the space provided so as to be concave upwardly, and the ends of the largest of the leaves, namely leaf 31, are flat or even reversely bent to provide a smooth abutting surface 38, 39 near the ends of the cheekwood 20.

The leaves are bundled together to form a compound unitary spring by means of a clamp 40. This clamp is provided with inwardly turned tabs 41, 42, as shown in Fig. 3, which are pressed inwardly after the leaves are assembled within the U-shaped clamp body. In order to prevent relative movement between the leaves, each of them has a convex offset portion at its center which mates with corresponding portions on the adjacent leaves as indicated at 44. Similarly, the clamp 40 may include an internal dimple to mate with the offset center portion of the leaf 35, the smallest in the series.

In accordance with one of the aspects of the invention means are provided for maintaining the improved spring 30 axially centered under the cheekwood 20 with which it cooperates, while allowing the spring a limited amount of rotational freedom so that it may accommodate itself to cocking movement of the cheekwood. That is to say, a restraining means is provided which allows the spring to bodily "teeter-totter" under the cheekwood through a limited angle. In the present instance this is accomplished by providing the clamp 40 with a downwardly extending lug or pin 46 which mates with an oversized hole 48 in the bottom of the channel 19 of the knife bar. If desired, the bottom surface 49 of the clamp 40 may be made convex as disclosed in Figs. 2 and 4 to permit limited rocking of the spring 30.

As a result of the above-outlined construction, it has been possible to operate printing presses for extended periods at the highest letter press speeds without objectionable breakage of the springs. In certain tests the improved springs operated satisfactorily at the end of a twelve week test period whereas conventional coil springs had failed in the identical type of service in less than one week of operation. This is obviously advantageous, not only because of the reduction in spring cost but also because of the saving of time on the part of the press operator who normally must shut the press down periodi-

cally to inspect the cheekwoods and to replace the springs which have been broken. Since frequent shutdown of the press is expensive, it has often been the practice in the past to allow a large portion of the cheekwood springs to break and to remain in place, the load being assumed by the remaining unbroken springs. However, this practice greatly reduces the effectiveness of the cheekwoods and jeopardizes the entire cutting operation.

Since a disproportionate improvement has been found, as a practical matter, to have resulted from what appears, at first impression, to be a relatively simple change of construction, considerable effort has been spent to determine the reasons for the successful operation and to uncover the basically new principles inherent in the disclosed spring. In order to fully appreciate the improvement it is necessary to understand that modern presses operate at a speed of approximately 50,000 papers per hour which corresponds to a cutting rate of about fourteen operations per second or more. Since the cut-off cylinder and the cylinder with which it cooperates are both nonyielding, the effect is the same as fourteen hammerblows applied to the cheekwoods each second over long periods of press operation.

To complicate matters such blows are not applied in a manner to cause the cheekwood to be moved flatly inward but are applied in a manner which frequently causes severe up-ending or cocking of the cheekwoods. The reason for this is that newspapers are made up of a large number of webs which are run together and folded prior to being fed into the cutter. The thickness of the paper is generally considerably greater at the fold than it is several inches distant from the fold. Accordingly, as the cut-off cylinder 40 rotates the affected cheekwood into contact with the folded portion of the paper, an impact is imparted to the cheekwood from the fold or high point of the paper. This causes one end of the cheekwood to be driven radially inward to a much greater extent than the opposite end of such cheekwood. In addition, other minor irregularities caused by accumulations of ink and paper dust, for example, may result in the cheekwood being forced inwardly in a cocked position.

In the conventional construction employing coil springs, the spring is recessed over a considerable portion of its length in a hole drilled in the bottom of the knife bar channel 19. Relatively few loops of the coil spring are therefore unguided or free-floating. As a result, the compression of the spring combined with the cocking of the cheekwood causes the force to be applied to the spring at an angle to the spring axis. A careful study of broken springs removed from conventional cut-off cylinders indicates that the upper loops or convolutions of the spring are forced against the mouth of the hole in which the spring is received, and therefore, assume the greater share of the loading. As a result of the non-axial concentrated stress, breakage takes place generally in the upper portion of the spring.

Still another factor which causes breakage of conventional springs is the fact that "bottoming" occurs, in other words, at least a portion of the adjacent spring convolutions are forced into contact with one another thereby providing an unyielding rather than a resilient stop for the cheekwoods. Such bottoming combined with non-axial loading can be readily demon-

stated to cause pinching of one or two spring convolutions resulting in severe localized stress and consequent breakage. This is to be contrasted with the improved spring disclosed herein in which bottoming is substantially impossible since the spring in its fully pressed or flattened condition coincides dimensionally with the channel in which it is received. Furthermore, movement of the cheekwood through the full range permitted by the slotted apertures 26 therein may take place without running any danger whatsoever that the spring will be suddenly converted into a non-resilient abutment as is the case with conventional coil springs.

Particularly noteworthy is the operation of the present spring under conditions causing end-to-end tilting or cocking of the cheekwood. As stated above, the engagement between the lug 46 of the spring 30 and the cooperating hole 43 in the knife bar is sufficiently loose to permit corresponding tilting of the spring through a limited angle. If, for example, the left-hand portion of the cheekwood 20 (Fig. 2) is deflected inwardly to a greater extent than the right-hand portion, a greater force tends to be applied to the spring at the surface 38 than is applied at the opposite end of the spring at surface 39. However, instead of the two halves of the spring acting independently, a compensating effect sets in: As the left-hand portion of the spring is tilted downwardly, the right-hand portion is free to move upwardly through a limited arc. As a result, the cantilever mounting of the spring is angled so that the left-hand portion is stressed to a lesser extent than it otherwise would be. This effect occurs only through a limited angle, however, in the preferred construction since, upon further downward movement of the left-hand portion of the cheekwood, engagement occurs between the lug 46 and the walls of the cooperating hole 43. Any excessive downward displacement of the left-hand portion of the spring is, therefore, increasingly resisted by the resulting cantilever deflection of the spring. In operation as the cheekwood rotates into contact with the cylinder which cooperates with the cut-off cylinder, inward movement is resisted to an extent which is dependent, to a large extent, upon the average amount of inward movement. There is substantially no danger of breaking a spring even when a particularly heavy load is encountered by one of the associated cheekwood.

It has been stated above that a limited amount of bodily tilting of the spring may take place upon cocking of the cheekwood with which it cooperates. An advantage is inherent in this feature which deserves specific mention. The spring as a result of such construction is inherently self-equalizing, that is, in normal operation the amount of force exerted at the surface 38 is substantially the same as that exerted by surface 39. Thus, as long as the cheekwood 20 remains relatively coaxial with the cut-off cylinder, all portions of the spring will be stressed uniformly. This situation is considerably different from that in which a plurality of coil springs are used and in which any non-uniformity in the length or restoring characteristics of such springs causes a single spring to absorb more than its share of the load with the obvious possibility of breakage.

Tests have also shown that the success of the spring may be due to considerable extent to the energy storage and absorption characteristics. Any spring is inherently an energy storing device, and it is necessary to increase the thickness of a spring of any type until the stress-strain ratio is such as to produce the desired restoring force. This has, in the past, made it necessary to increase the wire size so that a maximum amount of energy could be stored in a small volumetric space, with the result that the springs have been relatively stiff and inflexible. As a result of using the present construction, it will readily be seen that the spring, lying longitudinally under its cooperating cheekwood, utilizes the available space for energy storing purposes to a much greater degree than is possible with a coil spring or even a series of coil springs. In other words, the improved spring utilizes the available space for energy storage purposes more efficiently than any other spring construction of which I am aware. And, since only one spring is required per cheekwood, the construction reduces the number of parts and thereby makes the cutting assembly much cheaper to construct, assemble, and maintain. The knife bar may be more cheaply constructed since only a small number of relatively shallow holes 43 need be provided.

With regard to the energy absorption it will be apparent to one skilled in the art that the present leaved construction provides a large rubbing surface both between adjacent leaves and at the areas 38, 39 adjacent the cheekwood. This produces a snubber-like action which tends to reduce rebound of the cheekwood thereby increasing the life of both the cheekwood and the spring itself. Any tendency toward overtravel of the cheekwood due to impact is substantially eliminated.

I claim as my invention:

40 A printing press cut-off cylinder having a knife bar defining a longitudinal outwardly facing channel, a cutting blade centered in said channel, a series of cheekwoods lying in said channel on each side of said blade with means for limiting 45 the outward movement of said cheekwoods, a bowed leaf spring arranged in said channel under each of said cheekwoods, each of said leaf springs having a plurality of laminations in rubbing contact with one another, each of said leaf springs being symmetrically arranged under the associated cheekwood and having at its ends bearing surfaces for pressing engagement with the end portions of the underside of the associated cheekwood for rubbing thereagainst when the cheekwood is depressed, and means at the center of each of said springs for maintaining the spring in a fixed position longitudinally of said channel while permitting limited rocking movement of the spring bodily in the channel in response to cocking of the cheekwood.
